UNITED STATES PATENT OFFICE

141,410

DESIGN FOR A DISPENSER FOR CIGARETTES OR LIKE ARTICLES

Ralph E. Myers, Kansas City, Mo.

Application August 21, 1944, Serial No. 114,955

Term of patent 7 years

(Cl. D85—2)

To all whom it may concern:

Be it known that I, Ralph E. Myers, a citizen of the United States, residing at Kansas City, in the county of Jackson and State of Missouri, have invented a new, original, and ornamental Design for Dispensers for Cigarettes or like articles, of which the following is the specification, reference being had to the accompanying drawing, forming part thereof.

Fig. 1 is a perspective view of a dispenser for cigarettes or like articles, showing my new design; Fig. 2 is a side elevational view; and Fig. 3 is a front elevational view thereof.

I claim:

The ornamental design for a dispenser for cigarettes or like articles, as shown.

RALPH E. MYERS.
